Primary Examiner — Sheryl Lane*Assistant Examiner* — Nicole C Shiflet(74) *Attorney, Agent, or Firm* — Renner, Otto, Boisselle and Sklar, LLP(57) **CLAIM**

The ornamental design for a cooking plate with spiral shape, as shown and described.

DESCRIPTION

FIG. 1 is a perspective view of a first embodiment of a cooking plate with spiral shape showing my design.

FIG. 2 is a front elevational view thereof.

FIG. 3 is a cross-sectional view thereof taken along the line 3-3 of FIG. 2.

FIG. 4 is a perspective view of a second embodiment of a cooking plate with spiral shape showing my design.

FIG. 5 is a front elevational view thereof; and,

FIG. 6 is a cross-sectional view thereof taken along the line 6-6 of FIG. 5.

The broken lines in the drawings are included to show unclaimed subject matter and form no part of the claimed design.
